HEAT AND FIRE RETARDING CONSTRUCTION FOR VAULT DOORS

Harvey L. Henkel, Hamilton, Ohio, assignor, by
mesne assignments, to Herring-Hall-Marvin
Safe Company, a corporation of Ohio

Application July 1, 1949, Serial No. 102,621

6 Claims. (Cl. 109—65)

1

This invention relates to heat and fire retarding doors and jamb frames for vaults and the like, and more particularly to a door and jamb frame construction for vaults of the type used for storing records and the like to retard the passage of heat and fire to the interior of the vault for an appreciable time.

Vaults of the above type usually form a part of the fireproof masonry of a building, the vault door or doors usually being of metal or metal and concrete construction and hinged in a metal or metal and concrete frame which is set into the masonry of the vault. An appreciable spacing must be provided between the door jamb frame and the adjacent opening in the vault masonry in order, when installing the door jamb frame, to obtain accurate adjustment of the jamb in its opening with reference to the adjacent floor so that the doors will properly adjoin with each other and with the adjacent walls and sill of the door jamb in a substantial fire retarding fit when closed and remain in any open position without independent motion.

Experience has shown that in fires, flames and damaging heat pass into the vault between the door jamb frame and the masonry opening into the vault. It has heretofore been the practice when installing vault doors to leave ample space in the opening of the vault masonry to provide for the above adjustment and, after the door jamb frame is installed and adjusted, to fill this space between the masonry and door jamb frame with grout to prevent or retard possible passage of fire or heat through the space into the vault. New construction often settles or otherwise becomes slightly displaced from its original alignment, requiring subsequent realignment of the vault door. When grouted, however, this is not readily accomplished.

It is an object of this invention therefore to provide a vault door and door jamb frame construction which is free of grout, but at the same time capable of resisting or retarding the passage of flames or substantial heat into the vault for a predetermined appreciable time.

Another object of this invention is to provide a vault door and door jamb construction of the above character in which the means positioning and adjusting the door jamb frame in the vault opening are readily accessible for subsequent adjustment.

A further object of the invention is to provide a non-grout vault door construction which will retard the passage of flames and damaging heat into the vault for a predetermined period of fire condition for which the construction is designed, such as for two, four, six, etc. hours.

2

To accomplish the above and other important objects and advantages, which will become more apparent during the course of the following description, the invention consists in the parts and combinations hereinafter set forth with the understanding that various changes may be made therein, such as in the size, shape and arrangement of the parts, or by the substitution of equivalents, without departing from the spirit of the invention or exceeding the scope of the appended claims.

In order to make the invention more clearly understood, a preferred embodiment thereof has been made the subject of illustration in the accompanying drawing in which:

Figure 1 is a front elevational view of a vault door and door jamb construction according to this invention;

Figure 2 is a rear elevational view thereof;

Figure 3 is a horizontal cross-sectional view, partly broken away, taken along the line 3—3 of Figure 1;

Figure 4 is a vertical cross-sectional view, partly broken away, taken along the line 4—4 in Figure 1; and

Figure 5 is a cross-sectional view taken along the line 5—5 of Figure 3.

Referring more particularly to the drawings a fire resistant vault or storage room is represented by its front wall 1 which is of masonry construction, such as reinforced concrete, and which is provided with a rectangular entrance opening 2. Extending the length of each vertical wall 3 and across the top wall 4 of the door opening 2 is a continuous inwardly projecting rib 5, formed of the masonry of the wall 1, and having front and rear faces 6 and 7 parallel with the front and rear faces of the wall 1 and an inner face 8 perpendicular to the faces 6 and 7.

Fitted within the opening 2 is a rectangular door jamb frame 9 comprising vertical side frame pieces 10 and 11 joined together at their upper ends by a horizontal top frame piece 12, and at their lower ends by a horizontal, relatively thin sill piece 13 which rests on the floor of the vault entrance. The frame pieces 10, 11 and 12 are of box construction consisting of a front plate 14 and a rear plate 15 parallel therewith and joined thereto by an outer plate 16 and an inner plate 17. As seen in Figures 3 and 4, the front plate 14 extends transversely somewhat beyond the outer plate 16 to form a peripheral flange 18 along the front of the side and top frame pieces 10, 11 and 12.

The outer plate 16 extends rearwardly at right angles to the front plate 14, then inwardly parallel with the front plates toward the inner plate

55

17 and then rearwardly to the back plate 15 to form a step or shoulder 19. The inner plate 17 is contoured transversely according to the transversal edge contour of a particular door to be used. For example, the vertical plates 17 may be formed with a vertical groove 20 to receive a corresponding tongue 21 on the vertical edge of the door, and the top inner plate 17 may be formed with a forwardly facing angular flange 22 to fit complementary flanges 23 on the upper edges of the doors.

At intervals along the outer edge of the door jamb frame the outer plates 16 are cut away and fitted with depressed inserts 24 preferably provided with a stiffened or reinforced bottom wall 25. Screw threaded through the bottom wall 25 in each insert 24 is a screw 26 having a conical head 27 and fitted with a lock nut 28. The space within the frame pieces 10, 11 and 12 is preferably filled with concrete or other fireproofing and heat resistant material 29.

Detachably secured along the outer edge of the back plates 15 of the frame pieces 10, 11 and 12 respectively, by screws 30, so as to extend outwardly beyond the outer edges of these back pieces and parallel therewith, are clamping flange bars 31.

Doors 32 of any suitable fire resistant vault type are swung in the door jamb frame 9 by means of hinges 32' secured to the vertical frame pieces 10 and 11. The doors 32 illustrated are of sheet metal and concrete construction consisting of a front plate 33, a rear plate 34 and edge plates 35. Concrete fills the space between the front and rear plates except for a space 36 adjacent the rear plate necessary to accommodate boltwork which is designated generally as 37. The upper edge plates of the doors are formed with the angular flanges 23 complementary to the flange 22 to interfit therewith as shown in Figure 4, and the free vertical edge plates of the doors may be formed with similar complementary and interfitting flanges (not shown). The outer vertical edge plates of the doors are formed with the tongues 21 abovementioned which fit within the groove 20 in closed position of the doors as seen in Figure 3. A slight spacing is provided between the contiguous edges of the doors and the contiguous edges of the doors and door jamb frame to permit expansion without buckling.

To install, the wall opening 2 should be accurately constructed with the sides and rib 5 square and plumb and with the width and height dimension such as to have no more than one-half inch spacing between the opening and the outer plates of the door jamb frame when installed therein. With the back flange bars 31 removed, the door jamb frame is slid into the opening from the front of the vault until the flange 18 of the front plate 14 bears firmly against the front surface of the wall. The top flange bar 31 is now attached to the top frame piece 12 by means of its screws 30 so that it bears against the rear face of the rib 5. The screws 28 are next backed out in the vertical side frame pieces 10 and 11 until their heads bear firmly against the side walls of the opening 1 and are adjusted until the door jamb frame is centered in the opening with the spacing between side frame pieces and opening walls equal on both sides. As noted above this space should not exceed one-half inch.

The side flange bars 31 are now attached to the vertical frame pieces 10 and 11 and the top flange bar temporarily removed to adjust the screws 26 in the top frame piece into tight engagement with

5
10

the top wall of the opening 2. Next the top flange bar is reattached and the doors swung open as a test to find whether they bind or will not remain in any open position without independent movement. If binding is present or the doors fail to remain stationary in any position, the screws 26 are readjusted until correction is obtained, making sure that either the top flange bar or the side flange bars 31 are attached.

The construction may be easily modified to adapt it for different times of effective heat and flame retarding, such as for two, four, six hours, etc., simply by changing the width of the frame pieces of the vestibule. For example, in a four hour construction the width of the frame pieces between the edge plates may be 3½ inches and increasing this dimension to 6¼ inches the construction is effective for six hours.

It will be noted in Figures 2 and 3 that the rib 5 not only forms an abutment cooperating with the flange bars 31 to secure the door jamb frame in the vault wall opening but the rib 5 also cooperates with the shoulder or step 19 to provide a baffle to inhibit the passage of flame through the space between the door jamb frame and the wall opening when the front plate 14 initially buckles outwardly under heat. Although the front plate 14 buckles outwardly under heat this is accompanied by an inward movement of the shoulder 19 which seals closely against the forward face of the rib 5 to effectively block passage of flame and heat as the time of heating advances.

As an example of the heat retarding characteristic of this invention, tests performed under fire conditions on a six hour construction showed that at a furnace temperature of 2150° maintained for a period of six hours outside the vault at the door, a thermocouple reading at the flange bars 31 showed a temperature of only 250° F. at the end of the six hour period.

It will be observed from the drawings that the angular flange interfit between the doors and the upper edge of the door and door jamb frame will provide for free door swinging and for expansion and still maintain a flame seal. On the hinge edges of the doors where expansion movement may be blocked by the hinges it is advisable to provide a supplemental flame seal in the form of a laterally curved, resilient metal strip 39 between the tongue 21 and the bottom of the recess 20. The sill, it is found, will buckle upwardly under heat to seal the small clearance space between the bottom of the doors and sill.

55
I claim:

1. A non-grout, fire and heat retarding door construction for vaults and the like having a rectangular access opening in a wall thereof comprising a rectangular door jamb frame having side and top frame members of box form comprising inner, outer, front and rear plates secured within said opening with the side and top frame members spaced laterally from the corresponding side and top faces of said opening, an inwardly projecting rib formed on and extending continuously and longitudinally along the side and top faces of said opening and intermediate the front and rear faces of the wall, and an outwardly projecting shoulder formed on and extending continuously and longitudinally along the side and top frame members and overlapping but spaced from said rib to provide baffle means in the space between said frame and wall, and door means hinged to said frame.

70
75
2. A non-grout, fire and heat retarding door

construction for vaults and the like having a rectangular access opening in a wall thereof comprising a rectangular door jamb frame secured within said opening, said frame comprising vertical side box frame pieces joined at the upper ends thereof by a horizontal box frame piece and at the lower ends thereof by a flat sill piece, the said box frame pieces each having an outer plate laterally spaced respectively from the corresponding face of said opening, an inner plate, a front plate and a rear plate, an inwardly projecting continuous rib formed on and extending longitudinally along the side and top faces of said opening intermediate the front and rear faces of the wall, the outer plate respectively of said frame pieces each being formed with an inwardly extending step forming a continuous shoulder extending longitudinally along said frame pieces and overlapping but spaced from said rib to provide baffle means in the space between said frame and wall, and door means hinged on said frame.

3. A non-grout, fire and heat retarding door construction for vaults and the like having a rectangular access opening in a wall thereof comprising a rectangular door jamb frame secured within said opening, said frame comprising vertical side box frame pieces joined at the upper ends thereof by a horizontal box frame piece and at the lower ends thereof by a flat sill piece, said box frame pieces each comprising a front plate and a back plate parallel thereto and joined thereto by an inner and an outer plate, said front plates extending beyond the outer plates to form a flange engaging the front face of said wall, an inwardly projecting continuous rib having parallel front and back faces formed on and extending longitudinally along the faces of said opening intermediate the front and back faces of the wall, the outer plate of each of said frame pieces being formed with an inwardly extending step extending longitudinally therealong and forming a continuous shoulder overlapping but spaced from the front face of said rib to provide a baffle in the space between said frame and wall, strip like flange pieces detachably secured to said back plates of the frame pieces and engaging the rear face of said rib to secure said frame in the opening, and door means hinged to said frame.

4. A non-grout, fire and heat retarding door construction for vaults and the like having a rectangular access opening in a wall thereof, comprising a rectangular door jamb frame having side and top frame members of box form comprising inner, outer, front and rear plates secured within said opening with the side and top frame members spaced laterally from the corresponding side and top faces of said opening, an inwardly projecting rib formed on and extending continuously and longitudinally along the side and top faces of said opening and intermediate the front and rear faces of the wall, and an outwardly projecting shoulder formed on and extending continuously and longitudinally along the side and top frame members and overlapping but spaced from said rib to provide baffle means in the space between said frame

and wall, screw means threaded in said frame and extending outwardly from the top and side members thereof and engaging the top and side faces of said opening, said screw means being accessible for manipulation through the space between said frame and wall to adjust the frame relatively to the opening in the plane thereof, and door means hinged on said frame.

5. A non-grout, fire and heat retarding door construction for vaults and the like having a rectangular access opening in a wall thereof, comprising a rectangular door jamb frame secured within said opening, said frame comprising vertical side box frame pieces joined at the upper ends thereof by a horizontal box frame piece and at the lower ends thereof by a flat sill piece, said box frame pieces each comprising a front plate and a back plate parallel thereto and joined thereto by an inner and an outer plate, said front plates extending beyond the outer plates to form a flange engaging the front face of said wall, an inwardly projecting continuous rib having parallel front and back faces formed on and extending longitudinally along the faces of said opening intermediate the front and back faces of the wall, the outer plate of each of said frame pieces being formed with an inwardly extending step extending longitudinally therealong and forming a continuous shoulder overlapping but spaced from the front face of said rib to provide a baffle in the space between said frame and wall, screw means threaded in said frame pieces and extending outwardly from the outer plates thereof and engaging the side and top faces of said opening, said screw means being accessible through the space between the frame and wall to adjust the frame relative to said opening in the plane thereof, strip like flange pieces detachably secured to said back plates of the frame pieces and engaging the rear face of said wall about said opening to secure said frame in the opening, and door means hinged to said frame.

6. Door jamb construction of the character described, comprising, in combination, a wall having an access opening, box like side and top frame pieces each comprising a front plate, a rear plate and inner and outer side plates joining said front and rear plates, the outer plates being inwardly stepped intermediate the front and rear plates, said outer plates being disposed close to the side and top faces of said wall opening and the side faces of said wall opening being outwardly stepped to match the inward steps of the outer frame plates.
